UNITED STATES PATENT OFFICE.

ELIAS ABRAHAM, OF NEW LISKEARD, ONTARIO, CANADA, ASSIGNOR OF ONE-FOURTEENTH TO HENRY HARTMAN, ONE-FOURTEENTH TO DANIEL T. K. MCEWEN, ONE-FOURTEENTH TO ALBERT A. MORGAN, ONE-FOURTEENTH TO MICHAEL ABRAHAM, ONE-FOURTEENTH TO WILLIAM TAYLOR, ONE-FOURTEENTH TO KALIL ABRAHAM, AND ONE-FOURTEENTH TO FRANCIS LOUDEN SMILEY, ALL OF NEW LISKEARD, CANADA.

HOTEL-INDICATOR.

No. 853,851.

Specification of Letters Patent.

Patented May 14, 1907.

Application filed November 23, 1906. Serial No. 344,772.

To all whom it may concern:

Be it known that I, ELIAS ABRAHAM, of New Liskeard, in the District of Nipissing, Province of Ontario, Canada, have invented 5 certain new and useful Improvements in Hotel-Indicators, of which the following is a specification.

This invention relates to improvements in indicators for hotels and the like and the objects of the invention are to provide a device 10 quickly and easily operated and which will indicate whether a given room is vacant or occupied and thus save confusion when a number of guests are arriving at the hotel at 15 the same time; and it consists essentially of a suitable casing having a plurality of transparent apertures in the front thereof, cards behind the apertures divided into two parts each being of a size to fill the aperture and 20 having indicating words thereon, a plurality of depressible levers adapted to individually operate the indicator cards to move the same and change the part exposed, all as herein-after more fully set forth and described in the 25 accompanying specifications and drawings.

Figure 1 is a front view of my improved indicator. Fig. 2 is a sectional view through the same. Fig. 3 is an enlarged perspective detail of one of the levers in its depressed position. Fig. 4 is an enlarged perspective detail of one of the operating levers in its normal position. Fig. 5 is an enlarged perspective detail of one of the indicator cards and rod supporting the same.

35 In the drawings like letters of reference indicate corresponding parts in each figure.

Referring to the drawings *a* is the casing of any suitable or desirable construction, the front *b* thereof being provided with a plurality 40 of transparent apertures *c* of a number corresponding with the number of rooms in the hotel. These apertures are preferably arranged in rows as shown, the spaces *d* and *e* between being occupied with suitable advertisements which serve to hide the operating parts of the mechanism contained within the casing. Other advertisements may be placed 45 along the sides at *f* and *g* and at the bottom *h*. Conveniently the whole front may be made

of glass having one side of the same painted 50 leaving the apertures clear.

Opposite each of the apertures is an indicating card *i* formed in two equal parts *j* and *k* having the indicating words such as "Taken" and "Vacant" thereon, the size of 55 each part of the card being such that it will exactly fill the aperture opposite which it is located. The cards are supported on vertically extending rods *l* the upper ends of which have springs *m* connected thereto, the 60 upper ends of the springs being connected to suitable cross-bars *n*. The lower end of the rods are connected to the operating levers *o*. Preferably cross-bars *p* extend behind the rods to steady them in position. 65

While the operating levers *o* may be of any desired form yet it is preferable to make them as shown comprising the central portions *q* which are pivoted to cross-bars *r* secured in the sides of slots *s* provided in the casing and two arms *t* and *u* formed integral with the central portion and extending substantially at right angles to each other the arm *t* being connected to the rod *l* and the arm *u* having a button *v* on the end thereof. The outer 75 flat sides of the arms *t* and *u* are abutted by flat springs *w* supported on cross-bars *x* and operate to hold the levers in their depressed or normal position as illustrated in Figs. 3 and 4. 80

The portion *y* of the casing in front of the levers is preferably made inclined as indicated to accommodate the different rows of levers located one below the other.

Above the apertures in the register numbers *z* are placed which correspond with like numbers placed on the buttons *v* of the levers which operate the cards opposite the apertures. 85

In its use as a hotel register the device is 90 placed in a convenient place to be operated by the hotel clerk and as each guest arrives and selects a room the button on the lever corresponding to that room is depressed which moves the indicator card corresponding 95 to that room and causes the word "Taken" to appear in the aperture corresponding to the room thus indicating that

the room is occupied. As soon as the guest leaves the button of the lever is moved back to its normal position bringing the word "Vacant" into position in front of the aperture. 5 There is thus no danger of two guests being allotted the same room and the rooms may be allotted in quick succession and practically as fast as the buttons may be depressed. The device as well as being used in hotels 10 might be used as an indicator in an office building for offices or for indicating seats in the dining-room of a hotel or for other like purposes.

The device is exceedingly simple in construction and easy to operate and its installation in the hotels may be easily paid for by the advertisements contained on the outside thereof. Being wholly mechanical in its operation it is not liable to become out of order 15 as similar indicators operated electrically are. The connection between the levers and indicator cards being of a positive character prevents any failure in the operation.

While the mechanism has been described 20 with great particularity of detail yet it will be readily understood that changes may be made therein within the scope of the appended claims without departing from the spirit of the invention.

30 What I claim as my invention is:—

1. In a register for hotels and the like the combination with the casing having the front thereof formed with a plurality of apertures of a plurality of indicator cards each divided 35 into two parts having indicating words on each part, the size of each part being such that it fills the space of the aperture corresponding thereto, a plurality of depressible levers extending externally to the casing, a 40 spring for each lever for holding the same in a normal or depressed position and connecting means extending between the levers and the cards whereby a depression of the lever moves the corresponding card and causes the 45 part exposed through the aperture to be changed as and for the purpose specified.

2. In a register for hotels and the like the combination with a plurality of indicator cards of a plurality of rods supporting the 50 same, means engaging with the upper ends of the rods for holding the same in position, a plurality of depressible levers connected to the rods and adapted to raise and lower the same and a spring for each lever for holding 55 the levers in their normal or depressed positions as and for the purpose specified.

3. In a register for hotels and the like the combination with a plurality of indicator cards, a plurality of vertically extending rods 60 supporting the same, springs connected to the upper ends of the rods, a plurality of depressible levers connected to the rods and adapted to raise and lower the same and means for holding the levers in their normal

or depressed position as and for the purpose 65 specified.

4. In a register for hotels and the like the combination with a plurality of indicator cards, a plurality of vertically extending rods supporting the same, springs connected to 70 the upper ends of the rods, a plurality of depressible levers connected to the rods and adapted to raise and lower the same and resilient means for holding the levers in their normal or depressed position as and for the 75 purpose specified.

5. In a register for hotels and the like the combination with a plurality of indicator cards of a plurality of vertically extending rods supporting the same, springs connected 80 to the upper ends of said rods, means for supporting the upper ends of the springs, a plurality of pivoted and depressible levers connected to the rods and adapted when operated to raise and lower the same, springs 85 abutting flat portions formed on said levers adapted to hold them in their depressed or normal position as and for the purpose specified.

6. In a register for hotels and the like the combination with the casing having the front thereof formed with a plurality of apertures, a plurality of indicator cards divided into two parts and having indicating words on each part, the size of the said parts being 90 such that they each fill the space of the aperture corresponding to the card, a plurality of vertically extending rods supporting the cards, springs connected to the upper ends of the rods, means for supporting the upper 95 ends of the springs, a plurality of levers pivoted to the casing extending therethrough having their inner ends connected to the rods, springs adapted to abut flat portions 100 formed on the levers and so hold them in 105 their normal or depressed positions as and for the purpose specified.

7. In a register for hotels and the like the combination with a plurality of indicator cards of a plurality of rods supporting the 110 same, means for supporting the upper ends of the rods, of operating levers for the rods comprising central pivoted portions having two arms integral therewith and substantially at right angles to each other, one extending external to the casing and having a 115 button secured thereto and the other connected to the rod, and flat springs adapted to abut the arms of the levers and so hold them in their depressed or normal positions as and 120 for the purpose specified.

Signed at New Liskeard, in the Province of Ontario, Canada, this fifteenth day of November, 1906.

ELIAS ABRAHAM.
